UNITED STATES PATENT OFFICE

ALBERT P. GILBERT, OF THIENSVILLE, WISCONSIN, ASSIGNOR TO GILBERT SHOE CO.,
OF THIENSVILLE, WISCONSIN

DESIGN FOR A CHILD'S SANDAL

Application filed February 20, 1931. Serial No. 38,740. Term of patent 7 years.

To all whom it may concern:

Be it known that I, ALBERT P. GILBERT, a citizen of the United States, and resident of Thiensville, in the county of Ozaukee and State of Wisconsin, have invented a new, original, and ornamental Design for a Child's Sandal, of which the following is a specification, reference being had to the accompanying drawing, forming part thereof.

The figure is a front perspective view of a child's sandal showing my new design.

I claim:

The ornamental design for a child's sandal, as shown.

In testimony that I claim the foregoing I have hereunto set my hand at Thiensville, in the county of Ozaukee and State of Wisconsin.

ALBERT P. GILBERT.
